UNITED STATES PATENT OFFICE

DUDLEY K. DOVELL, OF EL PASO, TEXAS, ASSIGNOR TO SULLIVAN MACHINERY COMPANY, A CORPORATION OF MASSACHUSETTS

DRILL STEEL RETAINER

Application filed November 4, 1930. Serial No. 493,423.

My invention relates to retainers, and more particularly to tool retainers for hammer rock drills.

An object of my invention is to provide an improved tool retainer. Another object of my invention is to provide an improved tool retainer whose component parts are simple and are readily manufactured and assembled. A further object of my invention is to provide the improved tool retainer in which the benefits of a shock absorbing spring separate from the side rod springs are secured, while yet the exterior of the tool retaining mechanism has only a single movable part, the resilient shock absorbing means being wholly housed within the casing of the drilling apparatus. Other objects and advantages of the invention will hereinafter more fully appear.

20 In the accompanying drawing, in which I have shown for purposes of illustration one form which my invention may assume in practice,—

Fig. 1 is a fragmentary side elevation of a 25 rock drilling mechanism showing the forward end of the latter provided with the illustrative embodiment of my invention.

Fig. 2 is an axial section through the forward end of the drilling mechanism of Fig. 30 1, the section being taken on a plane at right angles to the view of Fig. 1.

Fig. 3 is a front end view of the mechanism shown in Fig. 1.

Referring to the drawing, it will be noted 35 that my invention in its illustrative form is embodied in a drilling mechanism of the hammer type whose forward end is indicated at 1. This drilling mechanism comprises a chuck housing 2 held in assembled relation with the other parts of the drill by usual side rods 3, retainer springs 4, washers 5 and nuts 6. Within the chuck housing 2 is rotatably mounted a chuck driving sleeve 7 within which is secured a chuck member proper 8 40 having a polygonal bore 9 for the reception of the shank 10 of a drill steel 11. 12 is the collar of the drill steel. Rotation is imparted to the chuck driving sleeve 7 through a nut 14 having a sliding connection through 45 splines 15 with grooves 16 in the striking bar

17 of the piston of the drilling motor (not shown). The forward end of the chuck housing 2 is provided with a central opening 20 large enough to permit the free passage of the collar 12 of the drill steel 11. The opening 20 is surrounded by an inwardly turned flange 21 which provides a radially extending surface 22 against which a retainer spring 23 reacts. The other end of the spring engages an annular member 24 having an opening 55 therein slightly larger than the collar 12 of the drill steel and which is positioned just forwardly of the front end of the chuck member proper 8. A retainer yoke 25 having a yoke portion 26 adapted to be engaged by the collar 12 on the drill steel and prevent complete withdrawal of the latter, is provided at its rear end with a pair of retainer extending bearing portions 27 which are permitted to extend into the bore of the chuck housing 2 60 through elongated slots 28 formed in the forward portion of the chuck housing. The inner ends of these bearing portions 27 are received in recesses 29 in the annular member 24. Bosses 30 formed on the exterior of 65 the chuck housing are adapted to hold the retainer in retaining position when it is moved thereto, it being noted that the retainer may be sprung into retaining position readily due to the position of these bosses 70 near the free ends of the retainer yoke. The slots 28 are of sufficient length to provide for all possible forward movement necessary 75 adequately to absorb the impact of the steel without any engagement of the pivot portions 27 with the forward ends of the slots. Preferably the movement toward the rear end of the drill of the annular member 24 is limited by engagement of the bearing portions 27, with the rear ends of the slots 28 in a 80 position such that there is no engagement between the member 24 and the front end of the chuck member 8. Wear is thus minimized and, moreover, the retainer 25 is adapted to be held against loose swinging movement by the frictional engagement of the bearing portions 27 with the rear ends of the slots 28 under the pressure of the spring 23. 85 90 95

From the foregoing description it will be clearly apparent that I have provided a sim- 100

ple and improved tool retaining mechanism in which it is unnecessary to rely upon the resilience of the side rod springs, but in which there is provided a safely enclosed separate 5 spring for this purpose. It will be noted, moreover, that the disposition of the spring and the general arrangement of the parts, leaves the forward end of the drilling mechanism with but a single external movable part.

10 It will further be observed that the entire device is of a rugged construction.

While there is in this application specifically described one form which this invention may assume in practice, it will be understood 15 that this form of the same is shown for purposes of illustration and that the invention may be modified and embodied in various other forms without departing from its spirit or the scope of the appended claims.

20 What I claim as new and desire to secure by Letters Patent is:

1. In a tool retaining mechanism, a chuck for receiving a collared drill steel, a chuck housing for receiving said chuck and having 25 formed in its opposite side walls longitudinally elongated slots, a drill steel retainer yoke arranged externally of said chuck housing and having inwardly projecting portions extending into said slots, said yoke presenting an abutment against which the steel collar is adapted to strike, and means arranged within said chuck housing for resiliently supporting said retainer yoke in retaining position including a spring coaxial 30 with the chuck housing and a ring pressed by said spring and having engagement with said inwardly projecting yoke portions, said spring and ring being arranged to surround the drill steel supported in said chuck.

40 2. In a tool retaining mechanism, a chuck for receiving a collared drill steel, a chuck housing for receiving said chuck and having formed in its opposite side walls longitudinally elongated slots, a drill steel retainer yoke arranged externally of said chuck housing and having inwardly projecting portions extending into said slots, said yoke presenting an abutment against which the steel collar is adapted to strike, and means 45 arranged within said chuck housing for resiliently supporting said retainer yoke in retaining position including a spring coaxial with the chuck housing in advance of said chuck and a ring pressed by said spring and having engagement with said inwardly projecting yoke portions, said spring and ring being enclosed within said chuck housing and arranged to surround the drill steel supported in said chuck.

50 3. In a tool retaining mechanism, a chuck for receiving a collared drill steel, a chuck housing for receiving said chuck and having formed in its opposite side walls longitudinally elongated slots, a drill steel retainer 55 yoke arranged externally of said chuck hous-

ing and having inwardly projecting portions extending into said slots, said yoke presenting an abutment against which the steel collar is adapted to strike, and means arranged within said chuck housing for resiliently supporting said retainer yoke in retaining position including a spring coaxial with the chuck housing in advance of said chuck and a ring pressed by said spring and having engagement with said inwardly projecting yoke portions, said spring and ring being enclosed within said chuck housing and arranged to surround the drill steel supported in said chuck and said ring having bores therein receiving said inwardly projecting yoke portions.

4. In a tool retaining mechanism, a chuck housing having a bore, a chuck in said bore for receiving a collared drill steel, said chuck housing having formed in its opposite side walls longitudinally elongated slots opening into said bore in advance of said chuck, a pivoted retainer yoke arranged externally of said chuck housing and having end portions projecting through said slots into said bore, said yoke presenting an abutment against which the steel collar is adapted to strike, and a coil spring in said bore acting on said projecting end portions for yieldably maintaining said yoke in retaining position.

5. In a tool retaining mechanism, a chuck housing having a bore, a chuck in said bore for receiving a collared drill steel, said chuck housing having formed in its opposite side walls longitudinally elongated slots opening into said bore in advance of said chuck, a pivoted retainer yoke arranged externally of said chuck housing and having end portions projecting through said slots into said bore, said yoke presenting an abutment against which the steel collar is adapted to strike, a collar guided in said bore and engaging said projecting end portions, and a coil spring in said bore acting on said collar for yieldably maintaining said yoke in retaining position.

6. In a tool retaining mechanism, a chuck housing having a bore, a chuck in said bore for receiving a collared drill steel, said chuck housing having formed in its opposite side walls longitudinally elongated slots opening into said bore in advance of said chuck, a pivoted retainer yoke member arranged externally of said chuck housing and presenting an abutment against which the steel collar is adapted to strike, a collar member guided in said bore, one of said members having portions projecting through said slots to connect said yoke member to said collar member, and a coil spring in said bore encircling the drill steel and acting on said collar member for yieldably maintaining said yoke in retaining position.

7. In a tool retaining mechanism, a drill

chuck for receiving a collared drill steel, a chuck housing having formed in its opposite side walls longitudinally elongated slots, an annular member guided in said chuck housing, a coil spring arranged within said chuck housing for urging said annular member rearwardly, said annular member and spring being arranged in said chuck to surround the drill steel supported in said chuck, and a 5 drill steel retainer yoke member arranged externally of said chuck housing and pivotally mounted on said annular member, said yoke having side arms extending along the sides of the chuck housing and a transverse stop 10 portion connecting the forward ends of said side arms and against which the steel collar is adapted to strike, one of said members having portions projecting through said slots to connect said yoke member to said annular 15 member and said spring and annular member cooperating to yieldably maintain said yoke in retaining position.

8. In a tool retaining mechanism, a drill chuck for receiving a collared drill steel, a 20 chuck housing having formed in its opposite side walls longitudinally elongated slots, an annular member guided in said chuck housing, a coil spring arranged within said chuck housing for urging said annular member 25 rearwardly, said annular member and spring being arranged in said chuck to surround the drill steel supported in said chuck, and a drill steel retainer yoke member arranged externally of said chuck housing and pivotally 30 mounted on said annular member, said yoke having side arms extending along the sides of the chuck housing and a transverse stop portion connecting the forward ends of said side arms and against which the steel 35 collar is adapted to strike, one of said members having portions projecting through said slots to connect said yoke member to said annular member and said projecting portions being engageable with the rear ends of said 40 slots to limit rearward movement of said annular member, said spring and annular member cooperating to yieldably maintain said yoke in retaining position.

45 In testimony whereof I affix my signature.
50 DUDLEY K. DOVELL.
